Filed Sept. 8, 1959, Ser. No. 57,468

Term of patent 14 years

(Cl. D55—1)

Fig 1 is a perspective view of a surface-forming machine for sheet metal, showing my new design.

Fig. 2 is an elevational view thereof as seen from one side.

Fig. 3 is a similar elevational view as seen from the opposite side.

Fig. 4 is an enlarged fragmentary cross-sectional view as taken on the line 4—4 of Fig. 3.

The dominant features of the design are shown in the drawings in full lines.

The end of the machine not shown is substantially plain.

I claim:

The ornamental design for a surface-forming machine for sheet metal, substantially as shown and described.
